J. J. H. Stone of Philadelphia Penn.
Letter Patent No 2254 Dated Jan 30 1866
Design for the Base of Sheet Metal Vessels

The schedule referred to in these Letters Patent and making part of the same
Teall where it may concern.

Be it known that I, J. J. H. Stone, of the City of Philadelphia,
in the State of Pennsylvania, have invented or produced a new and ori-
ginal Design for the bases or lower ends of sheet-metal vessels of tea and
coffee-pots, of which the following is a full, clear and exact description, refer-
ring to the accompanying drawing, making a part of this spe-
cification, and showing an elevation of one of the said bases, as appliced
to a tea-pot.

The lower ends of sheet-metal tea and coffee-pots have
hitherto been made with straight sides, or the whole sides of the ves-
sel, straight from top to bottom; but a form more tasteful or conveni-
ent is now required for them, and this is the object of my present design.

It consists in giving to these vessels, a recessed or necked
base, substantially of the exterior form or shape shown in the draw-
ing; the part of the vessel, which is above the said base, see the faint
lines in the drawing, being of any suitable form or shape that the
particular requirement of the vessel may render proper.

In the said drawing, A. B. is the main base. It consists of
three main divisions, i. e., the middle part from c, to d, the bottom part from
d, to e; and the upper part from e, to f.

The lower side of the upper part (c-f) connects directly with
the upper side of the middle part (c-d).

DES. 2254

2

The lower side of the middle (c.d) connects directly with the upper side of the bottom part (d.e) and thus joined together, produce the recessed or neck portion, from center of the said base A.B

What I claim as my invention or production, and desire to secure by Letters Patent is

The recessed or necked base (A.B) herein set forth and described, as a Design for the lower ends or bases of structural vessels of tea and coffee sets.
